UNITED STATES PATENT OFFICE.

WILLIAM E. HOWELLS, OF PECKVILLE, PENNSYLVANIA.

ELECTRIC FIRE-ALARM.

1,128,141.

Specification of Letters Patent.

Patented Feb. 9, 1915.

Application filed January 7, 1914. Serial No. 810,781.

To all whom it may concern:

Be it known that I, WILLIAM E. HOWELLS, a citizen of the United States, and a resident of Peckville, in the county of Lackawanna and State of Pennsylvania, have invented a new and Improved Electric Fire-Alarm, of which the following is a full, clear, and exact description.

This invention relates to an electric fire alarm of that type including a heat responsive device which at a predetermined rise in temperature of the atmosphere will close an electric circuit including one or more alarms or other warning devices.

The invention has for its general objects to improve and simplify the construction and operation of apparatus of the class described so as to be reliable and efficient in use, comparatively simple and inexpensive to manufacture and so designed as to form a complete unitary or self-contained article.

Another object of the invention is the provision of an alarm device of the character referred to which embodies a cell or other source of current, a bell and a thermostatically actuated circuit-closing means which can be installed in any desired room or place to be protected, and if desired the apparatus may be used in connection with an external circuit including one or more bells or other warning devices and a source of current which will take the place of the cell within the device, there being adjustable means whereby the circuits can be closed in any desired temperature of the atmosphere.

Still another object of the invention is the provision of an alarm device which includes a casing which has removably mounted therein the working apparatus that constitutes a unitary structure and includes a bell, battery, thermostat, circuit closing means and the necessary circuit connections, and such unitary structure being fastened in the casing by means of a removable or adjustable element of the circuit closer, which element has on its outer end a hand which is movable over a temperature dial whereby the circuit closer can be adjusted to close the alarm circuits at any desired temperature.

With such objects in view, and others which will appear as the description proceeds, the invention comprises various novel features of construction and arrangement of parts such as will be set forth in the

following description and claims appended hereto.

In the accompanying drawings, which illustrate one embodiment of the invention, and wherein similar characters of reference indicate corresponding parts in all the views, Figure 1 is a front view of the alarm, showing the door of the casing thereof open and with parts of the device in section; Fig. 2 is a vertical section on the line 2—2, Fig. 1; Fig. 3 is a side view of the pointer and dial of the circuit closer setting means; Fig. 4 is a diagrammatic view of the alarm circuit; Fig. 5 is a detail sectional view showing means for connecting one terminal of the alarm device with an external circuit; the section being on line 5—5, Fig. 1; Fig. 6 is a front view of the alarm device removed from its casing and with a portion of the device in section; Fig. 7 is a perspective view of the base structure of which the various parts of the alarm device are mounted; and Fig. 8 is a perspective view of the frame or holder for the cell.

Referring to the drawing, 10 designates a casing of any suitable design, which has its front open and provided with a door 10^a whereby access to the alarm device within the casing is had. The casing is adapted to be mounted at any desired place within the room or other place to be protected, and it is of such a size as to be conveniently portable and hooked up by means of a suspension eye 24 or equivalent device arranged at the top of the casing, the casing being in actual practice about three by four by seven inches, although, of course, the size of the apparatus can be varied as desired.

The alarm device is a unitary or self-contained structure and is bodily insertible and removable from the casing 10, and it embodies a supporting structure or base plate *a*, as shown in Fig. 7, and an arm or member *a'* extending therefrom. Mounted on this plate is a suitable thermostat 11 which may be of the multiple disk or wafer type, as shown, and contains a volatile liquid, such as ether. The rear wafer has a stud 14 which passes through an opening 14^a in the supporting plate *a*, and on this bolt is a nut 15 which serves to removably fasten the thermostat to the supporting plate. A contact member or bar 12 extends vertically and diametrically across the front of the thermostat 11 and has its

upper end bent backwardly at 12^a, and terminates in a base 13 which extends behind the thermostat and is formed with an eye 13^a which receives the fastening stud 14 of the latter, whereby the said stud forms a common fastening for the movable contact or bar 12 and the thermostat. The contact 12 is prevented from turning on the stud 14 as a center by means of a bracket 22 having spaced lugs 22^a which receive between them the double or bent portion 12^a of the contact element 12.

The movable or adjustable contact element of the circuit-closing means is carried by the arm a', and this movable contact element comprises a spindle 16 which passes through an opening a² in the arm a', and the inner end of the spindle is provided with an offset contact extremity 16^a which is adapted to coöperate with the lower or free end of the thermostatically actuated contact 12, and the outer end of the spindle passes through an opening 16^b in the left side of the casing 10, Fig. 1, so that the spindle 16 constitutes a means for fastening the alarm device within the casing. To adjust the movable contact the outer end of the spindle 16 is provided with a milled head 27, and in order to enable the contact to be set so as to cause the alarm to be energized at any desired temperature, the spindle 16 has a hand 17 which is adjustable over a dial 18 arranged on the left side of the casing 10. By turning the head 27 in one direction the contact extremity 16^a is moved away from the thermostatic contact 12, so that the circuit will be closed only at a higher temperature, and when the head 27 is moved in the opposite direction it brings the contact extremity 16^a of the spindle 16 closer to the thermostatic contact 12, and thereby causes the circuit to be closed at a lower temperature. The head 27 and the pointer 17 are removable from the spindle 16, which latter has a squared outer end 16^c, Fig. 6, so as to receive the head and pointer. The spindle is shiftable longitudinally in the openings a² and 16^b, so that it can be moved from the position shown in Fig. 1 to that shown in Fig. 6, to thereby enable the alarm device to be removed from the casing. To limit the movement of the spindle in inserting it in the opening 16^b, a collar or shoulder 19 is provided thereon so as to engage the member a' of the supporting plate a, and consequently the contact extremity 16^a will assume a position in line with the thermostatic contact element 12.

A bell B is fastened to the plate a in a position to occupy the lower part of the casing, the thermostat being arranged in the upper part thereof. This electric bell B is of ordinary construction and includes a base b, electro-magnets b', an armature b², a vibrating contact b³, a fixed contact b⁴, a

hammer b⁵, and a gong b⁶. One terminal of the electro-magnets b' is connected by a wire b⁷ with the thermostatic contact 12, the end b⁸ of such wire being clamped between the base 13^a of the contact 12 and the thermostat 11. The other terminal b⁹ of the electro-magnets is connected with the fixed contact b⁴, and is adapted to be grounded through the latter, spring contact b³ and frame or base b of the bell, such frame being connected in any suitable manner with the adjustable contact 16 of the circuit closer. A cell C is removably mounted in a holder D, which latter is constructed as shown in Fig. 8. This holder comprises a base d and arms d' so arranged as to grip and retain the cell C, which is of the dry type. The base d is securely fastened to the supporting base plate a by screws d², as shown in Fig. 6, and the frame b of the bell overlaps and bears on the left marginal portion of the base d, so that this frame or holder D, which is metallic, will be electrically connected with the bell. On the cell holder D is a contact member d³ which is disposed against the member a' of the supporting plate a, and on this member a' is a sleeve or contact d⁴ spaced and insulated from the contact member d³. The cell C has spring terminals c and c' which are adapted to bear against the contacts d³ and d⁴, and as the metallic sleeve d⁴ is electrically grounded on the adjustable contact element 16 of the circuit closer, and as the contact d³ is electrically connected with the frame of the bell D, it is obvious that the cell is included in circuit with the circuit closer and bell.

To understand in a general manner the electric circuit, reference is to be had to Fig. 4. When the thermostat expands and causes the contact 12 to engage the contact extremity 16^a, the circuit will be completed, so that the cell C will supply current which will energize the bell B. The connection between the contact element 16 and one terminal of the cell is represented in Fig. 4 by the wire x, but in the actual device the sleeve d⁴ and cell terminal c' are equivalent to this wire x. In the diagram the connection between the cell and bell is indicated by the wire x', but in the device this part of the circuit comprises the cell terminal c, contact member d³, base d of the cell holder D and frame b of the bell. The connection between the bell and thermostatic element 12 is designated by the wire b⁷, which is equivalent to the correspondingly designated wire in Fig. 1.

It may be desirable to use the alarm device in connection with an outside circuit, and consequently binding posts or equivalent means 20 and 21 are arranged on the casing, and these binding posts can be connected as shown in Fig. 1 with one or more bells e and a source of current f, and when

the apparatus is used in this manner the cell *c* within the casing can be dispensed with. The binding posts can be respectively connected by metal strips or wires 20^a and 21^a which lead to and are electrically connected with the sleeve *d*⁴ and base *d* of the cell-holding frame *D*, such conductors being fastened to the base plate *a* of the device. The complete circuit comprises the source of current *f*, bells *e*, binding post 20, conductor 20^a, sleeve *d*⁴, contacts 16 and 12, wire *b*⁵, the bell *B*, cell holder frame *D*, conductor 21^a, binding post 21 and source *f*. The bells *e* can be located in any place in the building where persons are most likely to hear the fire warning, and of course the thermostatic device will be mounted at that place where a fire is most likely to occur. The whole installation may be in a single building, or the thermostatic device may be arranged in an out building and the alarms in a dwelling. Obviously other uses of the apparatus are conceivable. As the conductors 20 and 21^a are fastened to the supporting plate *a*, which latter is removable from the casing, and as the binding posts 20 and 21 are fastened to the casing, a simple and effective connecting means between the conductors and binding posts is provided, such means being shown in Fig. 5. The binding posts include bolts and the heads 30 of such bolts are each provided with a shoulder 31, and each conductor terminates in a spring member or tongue 32 which engages under the shoulder as the alarm device is positioned in the casing.

To render the apparatus more complete the casing may have on its outside, at any suitable point, as for instance, the door 10^a, an ordinary thermometer 26.

From the foregoing description taken in connection with the accompanying drawings, the advantages of the construction and method of operation will be readily understood by those skilled in the art to which the invention appertains, and while I have described the principle of operation, together with the apparatus which I now consider to be the best embodiment thereof, I desire to have it understood that the apparatus shown is merely illustrative, and that such changes may be made when desired as are within the scope of the appended claims.

Having thus described my invention, I claim as new and desire to secure by Letters Patent:

1. A thermostatic alarm comprising a support, a thermostat, means for connecting the thermostat with the support, a contact element connected with the support by the said means and having a portion engaged with the thermostat for movement thereby, and an adjustable contact movable from the first contact.

2. The combination of a support, a ther-

mostat, a stud on the thermostat for fastening the same to the support, a fixed contact secured between the thermostat and support by the said stud and having a movable portion engaging a movable part of the thermostat, an adjustable contact related to the first mentioned contact, and an alarm circuit controlled by the contact.

3. In an alarm device, the combination of a support, a disk thermostat having a relatively fixed back portion and a movable front portion, a contact element fastened behind the thermostat and extending to the front and across the thermostat and engaging the movable portion thereof, and an adjustable contact movable toward and from the first mentioned contact, and a circuit controlled thereby.

4. In a device of the class described, the combination of a thermostat, a supporting stud connected with one side thereof and the other side being movable with temperature variations, a contact element doubled to straddle the thermostat and having one of its members provided with an eye for receiving the stud and the other member engaging the movable side of the thermostat for movement therewith, an adjustable contact associated with the first mentioned contact, and a circuit controlled by the contacts.

5. In a device of the class described, the combination of a thermostat, a supporting stud connected with one side thereof and the other side being movable with temperature variations, a contact element doubled to straddle the thermostat and having one of its members provided with an eye for receiving the stud and the other member engaging the movable side of the thermostat for movement therewith, an adjustable contact associated with the first mentioned contact, a circuit controlled by the contacts, a support to which the said stud is fastened, and means on the support for engaging the first mentioned contact for preventing the same from turning on the stud as a center.

6. A thermostatic alarm device comprising a support, a thermostat thereon, a contact on the support and movable by the thermostat, a member on the support, an adjustable contact mounted on the member, separate metallic pieces on the member, one of the pieces being connected with the adjustable contact, an electric bell having one terminal connected with the other metallic piece, a cell having resilient terminals arranged to engage the said pieces, and an electrical connection between the other terminal of the bell and the first mentioned contact.

7. A thermostatic alarm device comprising a support, a thermostat thereon, a contact on the support and movable by the thermostat, a member on the support, an

adjustable contact mounted on the member, 5
separate metallic pieces on the member, one
of the pieces being connected with the ad-
justable contact, an electric bell having one
terminal connected with the other metallic
piece, a cell having resilient terminals ar-
ranged to engage the said pieces, an elec-
trical connection between the other termi-
nal of the bell and the first mentioned con-
tact, conductors connected with the said
metal pieces respectively, and binding posts
connected with the respective conductors.

8. An electric alarm device comprising a
supporting structure, a thermostat thereon,
15 a contact moved by the thermostat and
mounted on the structure, an adjustable
contact mounted on the structure, a metal
piece connected with the adjustable contact,
a cell holder including a metal piece, a bell
20 having on terminal connected with the last
mentioned metal piece, an electric connec-
tion between the other terminal of the bell
and the first mentioned contact, and a cell
removably mounted in the holder and hav-
25 ing terminals arranged respectively to elec-
trically connect with the said metal pieces.

9. An apparatus of the class described
comprising a casing and an alarm device re-
movably mounted therein, said device com-
30 prising a support, a thermostat thereon, a
bell on the support, a circuit closer compris-
ing two contacting elements, one being ar-
ranged to be moved by the thermostat and
the other serving as a means for removably
35 holding the alarm device within the casing.

10. In an apparatus of the class described,
the combination of a casing having an open-
ing, an electric alarm device removably
mounted therein, said device comprising a
40 supporting structure including a member
having an opening arranged in alinement
with the opening in the casing, a thermo-
statically actuated contact element on the
said structure, an adjustable contact slid-
45 able in the opening of the said member and
engageable in the opening in the casing,
whereby the said adjustable contact forms a
locking means for holding the device in the
casing, means for connecting the two con-
50 tact in circuit with a source of current, and
a signal device mounted on the said struc-

ture and included in circuit with the said
contacts.

11. In an apparatus of the class described,
the combination of a casing having an open-
ing, an electric alarm device removably
55 mounted therein, said device comprising a
supporting structure including a member
having an opening arranged in alinement
with the opening in the casing, a thermo-
statically actuated contact element on the
60 said structure, an adjustable contact slid-
able in the opening of the said member and
engageable in the opening in the casing,
whereby the said adjustable contact forms
a locking means for holding the device in
65 the casing, means for connecting the two
contacts in circuit with a source of current,
a signal device mounted on the said struc-
ture and included in circuit with the said
70 contacts, an indicating element arranged
outside the casing and removably mounted
on the said adjustable contact, and a dial
outside of the casing and coöperating with
the indicating element. 75

12. In an apparatus of the class described,
the combination of a casing having an open-
ing, an electric alarm device removably
mounted therein, said device comprising a
supporting structure including a member
80 having an opening arranged in alinement
with the opening in the casing, a thermo-
statically actuated contact element on the
said structure, an adjustable contact slid-
able in the opening of the said member and
85 engageable in the opening in the casing,
whereby the said adjustable contact forms a
locking means for holding the device in
the casing, means for connecting the two
contacts in circuit with a source of current,
90 a signal device mounted on the said struc-
ture and included in circuit with the said
contacts, binding posts on the casing, and
conductors on the structure having inter-
locking engagement with the binding posts. 95

In testimony whereof I have signed my
name to this specification in the presence of
two subscribing witnesses.

WILLIAM E. HOWELLS.
